UNITED STATES PATENT OFFICE.

JAMES J. MILDON, OF BROOKLYN, NEW YORK.

STEAM-BOILER SYSTEM.

1,402,430.

Specification of Letters Patent. Patented Jan. 3, 1922.

Application filed November 20, 1918. Serial No. 263,310.

To all whom it may concern:

Be it known that I, JAMES J. MILDON, a citizen of the United States, residing at Brooklyn, county of Kings, State of New York, have invented certain new and useful Improvements in Steam-Boiler Systems, of which the following is a full, clear, and exact description.

My invention relates to improvements in steam boiler systems and has for its object to provide a system which can be installed by making additions to an ordinary horizontal return tubular boiler, already installed, for the purpose of increasing the efficiency of such boiler, to increase the efficiency of its furnace and to reduce or eliminate the presence of smoke usually discharged with the products of combustion.

It further has for its object to produce a simplified system in which the water in the boiler is caused to circulate, the parts of which system where sediment is liable to collect being capable of inspection and cleansing.

The following is a description of an embodiment of my invention,

Fig. 1 being a central longitudinal vertical section through the setting of a boiler to which my system is applied;

Fig. 2 is a horizontal section on the line 2—2, Fig. 1, the boiler being shown in dots and the connections thereto above the sectional plane being also shown;

Fig. 3 is a section of the setting on the line 3—3, Fig. 1, the boiler with its connections and the blast system being shown in elevation; and

Fig. 4 is a vertical section on the line 4—4, Fig. 1.

Referring more particularly to the drawings, 1 is a return tubular boiler of ordinary construction supported by lugs 2—2 and a setting 3 in the ordinary manner, my system being adapted to be applied to boilers already installed. 4 is the ordinary grate the rear end of which extends to a bridgewall 5, which, in my construction, is built up so as to leave a throat 6 whose lower surface preferably conforms substantially to the curvature of the boiler. With a boiler 6 feet in diameter and 18 feet long, having 70 four inch tubes, with a draft of about four-tenths (.4) of an inch, I make this throat about 63 inches in width and about 11 inches

5 in height, so as to constrict to some extent the exit passage from the fire-box and retain the gases therein until they become highly incandescent. The ends of the bridgewall are built up at 7—7 so as to close the angle between the sides of the boiler and the setting and these built-up portions 7—7 are provided with outwardly slanting forward faces 8—8, which serve to guide the gases toward the middle of the combustion chamber. At the rear of the bridgewall I provide an arch 9 located below the boiler and above which is a wall 10 extending upward to the boiler so as to close the spaces above this arch and between the sides of the boiler and the setting. 11 is a longitudinally extending pipe, which, with a boiler having the dimensions above referred to is about four inches in diameter. This pipe extends through the fire-box and combustion chamber adjacent to one wall of the setting, 70 passing beneath the arch 9 and through one of the built-up portions 7 and being connected at the front end of the boiler by a transversely extending inclined pipe 12 and coupling 13 to a nipple which enters the 80 boiler head. This nipple I preferably secure in the boiler head by removing a corresponding boiler tube and expanding the nipple in place. The rear end of the pipe 11 is connected by a transversely extending inclined pipe 12', coupling 13' and nipple to the rear boiler head in a similar manner through the opening left by the removal of the boiler tube above referred to. The rear end of the pipe 11 is lower than the front end 90 thereof, the drop being about one and one-half (1½) inches per foot. In order to provide easy inspection for the pipe 11, I provide in the couplings 14, 14' screw plugs 15, 15', which can be removed and when removed permit of easy inspection of the interior of the pipe 11 and the easy cleansing of the same. Connected to the coupling 14 is a blow-off pipe 16, provided with a cock 17 so that the boiler and system can be entirely emptied thereby. Connected with the boiler is the ordinary blow-off pipe 18, provided with its cock 19.

In the invert at the front of the boiler setting I provide an air blast pipe 20 having 105 a plurality of nozzles 21, ten such nozzles being shown in the present instance. The mouths of these nozzles are flattened horizontally and I space them about six inches apart, so that air discharged from said 110

nozzles will form an approximately continuous sheet over the fire in the fire-box. The right-hand end of this pipe 20 is connected with a three inch riser 22, which extends near 5 to the top of the furnace so that air coming in through the blast shall be taken from a heated source. Opening into the top of the riser is a small steam pipe 23, provided with a cock 24, the steam from which pipe, when 10 the cock 24 is opened, discharges into the riser 22, drawing in the warm air and causing it to be discharged, intermingled with the steam, into the front part of the fire-box, as shown in Figs. 1 and 2, the discharge being 15 in a somewhat downward direction toward the upper portion of the bridgewall beneath the throat 6. 25 is a chamber from which leads the connection 26 through which the products of combustion pass to the stack. 20 The chamber 25 and fire-box and ash pit are provided with doors 27, 28 and 29 in the ordinary manner. The combustion chamber 30 is constructed so as to slant downwardly from the bridgewall, as shown at 31.

25 In operating a system such as described, water is introduced in the boiler in the ordinary manner and after the fire has been started in the fire-box the cock 24 is opened to admit steam so as to cause air to be discharged 30 into the fire-box mixed with steam through the nozzles 21. This air mingling with the gases from the fuel assists in their more complete combustion, the partially consumed gases passing through the restricted 35 throat 6 until some of them impinge against the arch 9 and the wall above it, whereupon they are checked somewhat, thoroughly mixed and deflected downwardly away from the relatively cool boiler and toward the 40 rear portion of the pipe 11, passing outward in the combustion chamber 30, and thence through the tubes of the boiler to the chamber 25 and stack 26. The mingling of the gases with the air in this manner produces 45 substantially complete combustion, by reason of supplying the necessary oxygen for such complete combustion in such a way as to cause a proper commingling with the gases, thus avoiding loss by the escape of unburned gases. As the water in the pipe 50 11 becomes heated, a circulation is set up therethrough and through the boiler, the water flowing from the lower part of the pipe 11 to the upper part and thence into the 55 front end of the boiler, returning through the rear end of the boiler. This sets up a circulation through the system and a commotion in the boiler which, through its disturbance, causes the boiler to steam more 60 freely and also tends to remove the scale from the boiler so that the heat from the gases is more readily absorbed by the water in the boiler, with the result that the efficiency of the boiler is largely increased by 65 this circulation, as well as is the efficiency

of the furnace by the introduction of the air blast.

When it is desired to inspect the boiler proper that can be done by removing the ordinary manholes, and when it is desired to inspect or cleanse the pipe 11 that can be done by the removal of the plugs 15, 15', which are located at points which permit of easy removal and convenient cleansing of the pipe 11. The pipe 11 being straight, the removal of the plugs 15, 15' permits of thorough inspection and cleansing thereof. 75

The combustion which results from the use of the air blast above referred to is such as to approximately eliminate smoke from 80 the products of combustion discharged through the stack.

The substantially complete combustion of the gases, as above described, together with the greater heat absorption ability of the 85 boiler, because of the circulation, results in a considerable lowering of the temperature of the flue gases when leaving the boiler.

The presence of but four bends or angles in the circulating system and the absence of 90 pockets, results in a free circulation of the water and reduces the liability of sediment to collect and the formation of scale in the pipe.

As will be evident to those skilled in the 95 art, my invention permits of various modifications without departing from the spirit thereof or the scope of the appended claims.

What I claim is:

1. In a steam boiler system a horizontal 100 return tubular boiler and setting having a fire box at its forward end provided with a bridge wall and a combustion chamber to the rear of said bridge wall, in combination with a baffling arch behind said bridge wall 105 and depending from said boiler, a circulating pipe extending the length of said boiler through said fire box and combustion chamber and inclined downwardly toward the rear and connected to the heads of the boiler below the water line, the rear portion of said circulating pipe being exposed to the gases downwardly deflected by the baffling arch, and rearwardly discharging blast nozzles at 110 the front of said fire box. 115

2. In a steam boiler system a horizontal 120 return tubular boiler and setting having a fire box at its forward end, provided with a bridge wall, and a combustion chamber to the rear of said wall, in combination with a baffling arch behind said bridge wall and depending from said boiler, lateral baffles rising from said bridge wall and forming a contracted throat, a circulating pipe extending the length of said boiler through said fire box 125 and combustion chamber and inclined downwardly toward the rear, and connected to the heads of the boiler below the water line, the rear portion of said circulating pipe being exposed to the gases downwardly de- 130

flected by said baffling arch, and rearwardly discharging blast nozzles at the front of said fire box.

3. In a steam boiler system a horizontal return tubular boiler and setting having a fire box at its forward end provided with a bridge wall and a combustion chamber to the rear of said wall, in combination with a baffling arch behind said bridge wall and depending from said boiler, a circulating pipe extending the length of said boiler through said fire box and combustion chamber and

15 inclined downwardly toward the rear and connected to the heads of the boiler below the water line, the rear portion of said circulating pipe being exposed to the gases downwardly deflected by said baffling arch, and rearwardly discharging blast nozzles at the front of said fire box, the circulating pipe being located beneath one side of the 20 boiler and the connections between the ends of said pipe and the boiler heads being also inclined.

JAMES J. MILDON.
